No. 37,412.

Patented April 18, 1905.

UNITED STATES PATENT OFFICE.

DAVID W. AUSTIN, OF BROOKLYN, NEW YORK.

DESIGN FOR TILING.

SPECIFICATION forming part of Design No. 37,412, dated April 18, 1905.

Application filed March 16, 1905. Serial No. 250,528. Term of patent 3½ years.

To all whom it may concern:

Be it known that I, DAVID W. AUSTIN, a citizen of the United States, residing at Brooklyn, in the county of Kings and State of New York, have invented a new, original, and ornamental Design for Tiling, of which the following is a specification, reference being had to the accompanying drawing, forming part thereof.

The figure of the drawing is a plan view of 10 the tiling, showing my design.

I claim—

The ornamental design for tiling, as shown.

DAVID W. AUSTIN.
